(57) **CLAIM**

The ornamental design for a shoe, as shown and described.

DESCRIPTION

FIG. 1 is a front, left, and top perspective view of a shoe showing my new design;

FIG. 2 is a rear, right, and bottom perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged detail view of the encircled portion labeled "9" in FIG. 2.

The dash-dash broken lines in the drawings depict portions of the shoe that form no part of the claimed design. The dot-dash broken lines in FIGS. 2 and 9 are used to annotate an area of enlargement and form no part of the claimed design.

1 Claim, 9 Drawing Sheets
